UNITED STATES PATENT OFFICE.

JOHN KRASNODEMSKI, OF WAUSAU, WISCONSIN.

EXTENSION-TABLE.

1,140,466.

Specification of Letters Patent. Patented May 25, 1915.

Application filed June 3, 1914. Serial No. 842,735.

To all whom it may concern:

Be it known that I, JOHN KRASNODEMSKI, a subject of the Russian Czar, residing at Wausau, in the the county of Marathon and State of Wisconsin, have invented certain new and useful Improvements in Extension-Tables, of which the following is a specification, reference being had to the accompanying drawings.

10 This invention relates to extension tables, and has for its primary object to provide a table wherein supplementary leaves are carried by the two relatively movable main table sections.

15 The invention has for another and more specific object the provision of two pairs of leaves carried by the respective sections of the table top, said leaves being of a length equal to one-half of the width of the top, and means for mounting the respective pairs of leaves whereby they may be readily extended when the top sections are separated to occupy the spaces vacated by the respective sections.

25 The invention has for a further object to provide two pairs of leaves arranged in opposed relation and slidably mounted upon the body of the table, means on the respective top sections for sliding the pairs of leaves in relatively opposite directions when said sections are moved toward or from each other, and means for elevating the table leaves whereby the same may be readily grasped and extended to their operative 30 positions.

35 The invention has for still another object to produce an extension table having self-contained supplementary leaves whereby the extension of the table is greatly facilitated, and the manual labor incident thereto reduced to a minimum.

With the above and other objects in view, the invention consists in novel features of construction, combination, and arrangement 40 of parts as will be hereinafter referred to and more particularly pointed out in the specification and claims.

45 For a full understanding of the invention, reference is to be had to the following description and accompanying drawings, in which—

50 Figure 1 is a plan view showing the form of the relatively movable sections of the table top; Fig. 2 is a transverse section taken on the line 2—2 of Fig. 1; Fig. 3 is a similar view showing one of the table leaves in its

extended position; Fig. 4 is a longitudinal section taken on the line 4—4 of Fig. 3; Fig. 5 is a detail longitudinal section taken on the line 5—5 of Fig. 2; Fig. 6 is a bottom 60 plan view of one of the leaves and the hinged arm upon which the same is slidably mounted; Fig. 7 is a section taken on the line 7—7 of Fig. 6, and Fig. 8 is a detail fragmentary plan view, the table top sections being removed. Fig. 9 is a detail section taken on line 9—9 of Fig. 4.

Referring in detail to the drawings, 5 designates the bottom wall of the table body which is of rectangular form in plan, and is 70 mounted at its corners upon suitable supporting legs indicated at 6. Upon the marginal edges of the bottom 5 the upstanding side and end walls 7 of the table are mounted, said walls being secured by screws or 75 other analogous fastening means to the bars or beams 8 which are secured upon the bottom 5 of the table. These walls are preferably dove-tail at their ends in the supporting legs 6.

As shown in Fig. 1 of the drawings, the table top consists of two sections 9, each of which is of L-shape form, said sections having their longitudinally extending arms 10 extending in opposite directions and provided with interfitting tongues and grooves on their inner longitudinal edges indicated at 11 for engagement when the table is in its closed or normal position. Each of said arms 10 is of a width equal to one-half of the maximum width of the table top. These top sections 9 are slidably mounted for longitudinal movement on the upper edges of the side walls of the table, and each of the top sections has secured to its bottom face and 90 contiguous to its longitudinal edges a cleat 12 which is provided upon its inner face with a longitudinal rib 13. This rib is adapted to engage beneath a longitudinal shoulder 14 formed on the outer face of the 100 side wall of the table positioned adjacent its upper edge. In order to relieve the side walls 11 of undue strain due to any tendency of the table top sections to shift transversely, each top section is further provided upon its bottom face inwardly of and in spaced relation to the cleats 12 with a slide bar 15.

105 Each of these slide bars for a portion of its length is of rectangular form, and at its end extends through a recess formed in the top face of one of the table legs 6. A pin 16 projects downwardly from this latter end 110

of the slide bar and limits the inner movement of the table section by engagement with said leg. The inner end portion of the slide bar 15 is reduced in thickness, and is 5 slidably mounted upon the corresponding portion of one of the bars carried by the other section of the table top. These slide bars, as clearly shown in Figs. 2 and 3 of the drawings, are disposed for sliding engagement along the inner faces of the side walls 7.

To the bottom 5 of the table contiguous to one of the longitudinal bars 8 a dove-tail guide bar 17 is secured. This bar extends 15 in parallel relation to the bar or beam 8 for slightly more than one-half of the length of the table body and upon the same the slide block 18 is mounted, said block, of course, being provided in its bottom face with a 20 groove to receive said rib. A similar guide rib 19 is also secured to the inner face of the other longitudinal beam 8 adjacent to its upper edge and upon this guide bar a second slide block 20 is mounted. This latter slide block is arranged in a flange plate or holder 21 which is secured upon a depending bracket 22 fixed to one of the table top sections 9. The first named slide block 18 is centrally provided in its upper edge 25 with a notch or recess 23 to receive the lower end of an actuating element 24 which is fixed to the under side of the other table top section. Thus, it will be apparent that when the table top sections are moved with 30 relation to each other upon the upper edges of the side walls 7, the respective slide blocks 18 and 20 are correspondingly moved in relatively opposite directions.

25 indicates the supplementary leaves. 40 These leaves are equal in length to the width of the arms 10 of the table sections 9. The leaves 25 are preferably arranged in pairs, though it will be understood that a greater number may be provided if desired. Each 45 of the leaves has secured to its bottom face and along its opposite longitudinal edges, guides plates or rails 26, the inner edges of which are spaced from the surface of the leaf and are slidably engaged in the grooves 50 28 formed in the opposite edges of a block 27. This block is hinged as at 29 upon the inner end of an arm 30. To the outer end of each of said arms a block 31 is secured, and said blocks of the respective pairs of 55 leaf carrying arms are hinged as at 32 to the slide blocks 18 and 20 respectively. It will be noted that the arms 30 which are mounted upon the slide block 20 are longitudinally curved to a slight extent so that 60 the inner ends of the leaves mounted upon said arms are normally supported at a higher elevation than the outer ends of said leaves and are thus maintained in spaced relation to the other lower pair of table leaves 25 in the sliding movement of the

table top sections. In this manner liability of engagement of the respective pairs of leaves or the supporting arms with each other would be precluded, and interference by the same with the sliding movement of the top sections thus obviated. One of the end edges of one pair of table leaves is provided with a notch or groove 33 to receive the tongue on the longitudinal edge of one of the arms 10 of the table top, while the corresponding end edges of the other pair of supplementary table leaves are provided with tongues 34 for engagement in the longitudinal groove in the inner edge of the arm of the other top section. One of the 75 guide plates or rails 26 which are secured to the latter pair of leaves 25 is extended beyond one end of the leaf for engagement with the block 31, so as to avoid the possibility of mutilation of the tongue 34. 80

As will be observed from reference to Fig. 2 of the drawings, the lowermost pair of supplementary table leaves 26 which are mounted upon the slide block 18 are normally disposed in parallel relation to the bottom 5 of the table. In order to permit said leaves to be readily grasped and extended upon their supporting arms, I provide the lifting ribs indicated at 35. These ribs are suitably spaced from each other and secured to the bottom of the table 5. At one of their ends they are gradually curved or tapered so that the outer ends of the arms 30 which are hingedly mounted upon the block 18 will readily ride over the same. Therefore, as shown in Fig. 3 of the drawings, when the table top section to which the slide block operating member 24 is attached is moved with respect to the other top section, the lower pair of table leaves 105 and their supporting arms are, of course, also moved longitudinally over the bottom 5 of the table, and when the arms engage with the lifting ribs 35, the inner ends of said arms are forced upwardly or elevated, thus 110 also elevating the table leaves carried by said arms. To the bottom face of each of the table leaves at the opposite end thereto to that provided with the tongue or groove, a cleat 36 is secured. These cleats are of 115 similar shape in cross section to the cleats 12 of the table top sections and are adapted for engagement with the respective shoulders 14 in a similar manner when the supplementary leaves are extended to their operative positions. 120

From the foregoing description taken in connection with the accompanying drawings, the construction, manner of use, and several advantages of my improved extensible table will be clearly and fully understood. When the table top sections are in their closed normal positions, the respective pairs of supplementary leaves 25 occupy the relative positions with respect to each other 130

between the top of the table and the bottom 5 as shown in dotted lines in Fig. 1. The two top sections 9 are extended longitudinally upon each other until the end edges of 5 their arms 10 are in alinement. The respective pairs of leaves are normally located immediately beneath the arms 10 and moved with said sections. When the sections have been extended as above stated, the lowermost 10 pair of table leaves being elevated by the lifting ribs 35, as hereinbefore explained, the inner ends of one pair of table leaves are pulled outwardly upon the blocks 27 which are hinged to the arms 30 so that said leaves 15 will occupy the space which has been vacated by the arm 10 of the other table top section. The other pair of supplementary leaves 25 are extended in an opposite direction with respect to the first pair of leaves into the 20 space formerly occupied by the other of the arms 10. The cleats 12 and 36 on said arms are, of course, engaged with the longitudinal shoulders 14 on the respective side walls of the table, and the tongues or grooves on the 25 end edges of said leaves are engaged with the groove or tongue of the table top arms 10 as the case may be. When the leaves are thus arranged, the arms 30 will be angularly disposed between the inner ends of the leaves 30 and the respective slide blocks 18 and 20.

In this manner it will be seen that I have produced a simply constructed, as well as highly convenient and serviceable extension table, wherein a large number of supplementary table leaves are at all times contained within the table itself so that the operator is relieved of the excessive labor incident to the bodily removal or insertion of the leaves incident to the use of the ordinary table of this character. When the table sections are moved inwardly toward each other to their closed positions, the pins 16 engaging the upper ends of the table legs preclude all possibility of injury to the abutting edges of the table top sections by forcible engagement of the same with each other. My improved table is also very durable in its construction, and may be produced at small manufacturing cost.

50 While I have above described the preferred form, construction, and arrangement of the several elements employed, it will be understood that the device is, nevertheless, susceptible of considerable modification therein, and I therefore reserve the privilege of resorting to all such legitimate changes as may be fairly embodied within the spirit and scope of the invention as claimed.

What is claimed is:

60 1. In an extension table, relatively movable top sections each having a longitudinally extending arm, said arms being slidably engaged with each other and normally disposed in the same plane, and a pair of 65 slidably mounted supplementary table leaves

arranged beneath each of said arms and movable with the respective table sections, said pairs of leaves being adapted to be extended with respect to said arms when the top sections are separated to occupy the 70 space vacated by the arm of the other top section.

2. In an extension table, relatively movable top sections each having a longitudinally extending arm, said arms being slidably engaged with each other and normally disposed in the same plane, a pair of transversely disposed bars mounted beneath the arms of said top sections, a table leaf longitudinally movable upon each of said bars, 75 and means carried by the respective table top sections for sliding said pairs of supporting bars in relatively opposite directions when the top sections are separated, the table leaves mounted upon the respective pairs of 80 bars being adapted to be extended in relatively opposite directions to occupy the space vacated by one of the arms of the table top sections.

3. In an extension table, two relatively 90 movable top sections having slidably engaged longitudinal extensions, slidably mounted blocks, the respective top sections being provided with means engaging said blocks to slide the same, and a transversely 95 movable table leaf carried by each of said blocks and adapted to be extended when the top sections are separated to occupy the space vacated by one of said top sections.

4. In an extension table, relatively movable table top sections, slide blocks movable with the respective top sections, a transversely disposed bar hingedly mounted upon each of the slide blocks, and a supplementary table leaf mounted for longitudinal 100 sliding movement upon each of said bars, said table leaf being adapted to be extended upon the hinged bar when the table top sections are separated to occupy the space vacated by one of the top sections.

5. In an extension table, relatively movable top sections, a slide block slidable with each of said top sections, a pair of transversely disposed bars hingedly mounted upon each of said slide blocks, supplementary table leaves longitudinally slidable upon said bars and adapted to be extended with relation thereto when the top sections are separated to occupy the spaces vacated by said top sections.

6. In an extension table, relatively movable top sections, slide blocks movable with respect to said top sections, transversely extending arms hingedly mounted upon the respective slide blocks and disposed in different horizontal planes, a supplementary table leaf slidably mounted upon each of said bars and adapted to be extended when the table top sections are separated to occupy the space vacated by one of said sec- 125 130

tions, and means for elevating the lowermost hinged bars and the leaves mounted thereon.

7. In an extension table, the combination with a body including a bottom and side and end walls, of relatively movable top sections longitudinally slideable upon said side walls, longitudinal guide rails mounted upon the table body adjacent the respective side walls, blocks slidably mounted upon said rails, means secured to the respective table top sections and coöperating with said blocks to slide the same, a pair of transversely disposed arms hingedly mounted upon the respective slide blocks, a supplementary table leaf longitudinally slideable upon each of said bars, said hinged bars and the respective pairs of leaves being disposed in different horizontal planes, and means on the table bottom for coöperating with the lower pair of said bars at their hinged ends to elevate the same and the table leaves when the top sections are separated, the respective pairs of leaves being adapted to be extended upon the bars to occupy the space vacated by one of the table top sections.

8. In an extension table, top sections movable with relation to each other and having extensions slidably engaged with each other, and a table leaf permanently mounted beneath each of said sections for movement in a line at right angles to the line of movement of the top sections to occupy the space vacated by one of the extensions of said top sections.

9. In an extension table, top sections movable with relation to each other to space their abutting edges, said sections having relatively narrow longitudinal extensions disposed alongside each other and in the same plane and a table leaf permanently

mounted upon the under side of one of said top sections and transversely movable with respect thereto whereby said leaf may be extended to occupy the space between the opposed edges of the top sections when the latter are separated.

10. In an extension table, relatively movable top sections, a support mounted beneath one of said top sections for longitudinal and vertical movement, means on the top sections to move the support longitudinally when the top sections are separated, a table leaf slidably mounted upon said support, and stationary means coöperating with the support in the movement of the top sections to move the support in a vertical plane and position the leaf thereon whereby the same may be grasped and extended to occupy the space between the opposed edges of the separated top sections.

11. In an extension table, relatively movable top sections, having slidably engaged longitudinal extensions, a slide bar mounted beneath one of said top sections and movable therewith when said sections are separated, a transversely disposed support hingedly connected to the slide bar for movement in a vertical plane, a table leaf longitudinally slideable upon said support, and a stationary element coöperating with said support when the top sections are extended to move the support vertically and position the table leaf to be grasped and extended into the space between the opposed edges of the top sections.

In testimony whereof I hereunto affix my signature in the presence of two witnesses.

JOHN KRASNODEMSKI.
